UNITED STATES PATENT OFFICE

ROBERT C. PAIRMAN, OF BERKELEY, CALIFORNIA

PYROMETER

Application filed June 15, 1927. Serial No. 198,943.

This invention relates to pyrometers and like instruments, and especially to that type which depends upon the differential expansion of two elements for indicating temperatures.

Pyrometers of the above character usually consist of a casing provided with a dial which is graduated into degrees, Fahrenheit or centigrade as the case may be, to indicate temperature.

The casing is provided with a tubular extension, preferably constructed of a metal having a comparatively high coefficient of expansion. The expanding movement of the tube is transmitted through a rod having a low coefficient of expansion to a gauge movement, and this, in turn, actuates a pointer or indicator which swings over the graduated dial and thereby indicates temperature.

A number of temperature indicating instruments embodying the above elements and mechanism have been constructed and used but from a practical operating point of view have, in most instances, proven a failure, due to the following reasons: Back lash and lost motion has been encountered which could not be compensated; the link and gauge movements employed were difficult to adjust; the expanding and non-expanding elements employed would deteriorate or disintegrate, when exposed to high temperatures, and their coefficient of extension would gradually change, causing incorrect temperature readings to be indicated. The result is that temperature indicating instruments of this character have been practically abandoned in favor of electric or thermo-couple actuated pyrometers.

The object of the present invention is to generally improve and simplify the construction and operation of pyrometers of the character described by providing expanding and non-expanding elements which will stand high temperatures without danger of deterioration or change in their coefficient of expansion; by providing a link and connected gauge movement which may be readily and easily adjusted by providing means for positively taking up all back

lash and lost movement; and further by providing a link and gauge movement which is sturdy and substantial and reliable in operation when subjected to different uses.

The pyrometer is shown by way of illustration in the accompanying drawings, in which—

Fig. 1 is a front view of the pyrometer, said view being partially in section and partially broken away to show the operating mechanism.

Fig. 2 is a central, vertical, longitudinal section.

Fig. 3 is a cross section, taken on line 3—3 of Fig. 1.

Fig. 4 is an enlarged section on line 4—4 of Fig. 1.

Referring to the drawings in detail and particularly Figs. 1 and 2, A indicates a casing, consisting of a bottom section 2 and a circular side wall 3. Projecting through the lower portion of the side wall 3, as at 4, is a tubular extension 5, on the upper end of which is formed a head member 6 and a combination bearing and guide 7. The tube 5, together with the head member 6, is secured to the casing in any suitable manner and, as here indicated, by means of screws 8.

Secured in the lower end of the tubular extension 5 is a tube 9. The lower end of the tube is closed by means of a plug or the like indicated at 10, and mounted interiorly of the tube and guided thereby is a rod 11, the function of which will be hereinafter described. Slidably mounted in the tubular extension 5 is a plunger or connecting rod 12. This plunger rests on the upper end of the rod 11, and the upper end of the plunger is pivotally connected, as at 13, with a main actuating lever, generally indicated at 14. This lever is pivotally mounted, as at 15, in the bearing 7. The bearing is slotted lengthwise to form a guide for the lever 14, and the center portion is drilled to form a guide for the plunger 12; the upper end of the plunger being slotted, as at 16, (see Fig. 2) to straddle and connect with the main actuating lever 14.

Mounted within the casing A is a gauge

movement, which is generally indicated at B. This movement consists of a base plate 17 and a top plate 18 which are interspaced with relation to each other by means of 5 spacing posts, such as indicated at 19. Journaled between the plates is a spindle 20, and secured theron is a small spur gear pinion 21 which intermeshes with a segmental rack bar 22. This rack member 10 is pivotally mounted, as at 23, between the plates 17 and 18 and is provided with an adjustable lever extension 24 which is connected with the main operating lever 14 through means of a link 25.

15 The spindle 20 carries an ordinary pointer or indicator hand 26 and this is movable over a dial 27 which is graduated in degrees —Fahrenheit or centigrade—as particular uses may demand. The gauge movement, 20 generally indicated at B, which has been more or less specifically described, is a standard movement and no invention is claimed as far as the specific structure involved is concerned. The manner of 25 mounting the movement, however, is new and this will be described in detail.

By referring to Figs. 1, 2 and 3 it will be noted that one end of the base plate 17 is pivotally secured to the bottom section 2 of the casing by means of a screw or the like, such as indicated at 28. The opposite end of the base plate is secured to the bottom section 2 by means of a screw 29. The bottom section 2 is provided with an elongated 30 slot, as indicated at 30, where the screw 29 passes through, and it is thus possible to swing the entire gauge movement about the pivotal connection 28. This is important as it permits adjustment of the indicating hand 26 with relation to the graduated dial from a point exteriorly of the casing.

Mounted on the exterior or rear side of the bottom section 2 of the casing is a pair of posts, such as indicated at 31 and 32. The post 31 is adjustable and the post 32 is stationary as it is secured to the bottom section 2 of the casing by means of a screw 33. A threaded rod 34 is secured at one end, as at 35, to the post 31. The opposite 40 end of the threaded rod extends through the post 32 and it carries a pair of adjusting screws 36 and 37 and a set or lock screw 38 is provided. The pivot screw 29 extends through the post 31 and carries a pair of lock nuts 39 on its outer end.

If it is desired to adjust the pointer 26 with relation to the graduated gauge dial it is only necessary to loosen the set-screw 38 and the lock nuts 39 and one or the other of the adjusting-screws 36 or 37. For instance, if it is desired to swing the gauge movement about the pivot 28 towards the left, screw 37 is slackened and screw 36 is tightened. This will pull the block 31, the screw 29 and the gauge movement longitudi-

nally of the slot 30 towards the left and as the main operating lever 14 and link 25 are stationary, it will have the same effect upon the segmental rack 22 as if it were swung about its pivot towards the left-hand side 70 of the casing. In other words, the pinion 21, together with the spindle and the indicating hand 26, will swing contraclockwise, and when the desired adjustment is obtained it will only be necessary to tighten the several screws, lock nuts, and the adjustment will be maintained.

If it is desired to adjust the indicating hand in a clockwise direction the gauge movement is swung about the pivot 8 towards the right. This produces the same effect as if the segment is swung to the right and accordingly causes the pinion 21, spindle 20 and indicating hand to rotate in a clockwise direction. It is accordingly possible to 85 adjust the position of the indicating hand 26 either clockwise or contraclockwise with relation to the indicating dial without removing the indicating hand or dial and without disturbing any of the adjustments 90 within the casing. This adjustment, however, does not change the ratio of movement which depends upon several features, such as the distance between the pivots 13 and 15, the distance between the point 15 and the 95 upper pivotal connection of the link 25, and the position of the adjustable lever 24 with relation to the pivotal point 23. The ratio of the movement, which depends upon these 100 distances, can only be adjusted by changing the position of the extension 24 or by changing the position of the link 25 with relation to the main actuating lever 14. To permit such adjustment an adjustable plate 40 is 105 employed.

This adjustable plate 40 is slotted and it is secured to the upper end of the main operating lever 14 by means of a pair of screws, such as indicated at 41. The link 25 is pivotally secured to the upper end of the slotted plate, as at 42. By slackening the screws 41 the plate 40 may be adjusted upwardly or downwardly on the lever 14 and the distance between the points 15 and 42 may accordingly be adjusted, thereby 115 increasing or decreasing the leverage or ratio of the movement.

A similar adjustment is obtained by moving the adjustable lever 24 upwardly or downwardly with relation to the pivotal point 23. These adjustments are usually made in the factory when the instrument is being tested and once the adjustment has been properly made further attention is not required; hence the importance of employing an exterior adjustment if it is necessary to change the position of the indicating hand 26 with relation to the graduated dial.

The spindle 20 is provided with an ordinary hair spring in the manner of all stand-

ard gauge movements. This spring is indicated at 43 and it merely serves the function of taking up any play between the teeth of the segment 22 and the pinion 21. Slack 5 or play in the bearings or connections otherwise employed, for instance, the pivotal connections between the link 25 and the connections 13 and 15, is taken up by a spring 46; this being secured at one end to the casting and at its opposite end to the adjustable lever 24. This spring exerts a constant pull in the direction of arrow *a*. This pull takes up any slack in the connections of the link 25 and it tends to swing the main operating 10 lever about its pivot 15 in the direction of arrow *b*. As this is the case the lever exerts a downward pressure on the bearing 15 and the pivotal connection 13 and as such takes up any lost motion or play that may exist. 15 It further exerts a downward pressure on the plunger 12 and the rod 11 and maintains these members in constant and intimate contact with relation to each other and also with relation to the plug 10.

20 In actual practice the instrument has been employed for numerous purposes, such as taking stack temperatures, baking oven temperatures, lead bath temperatures, exhaust gas temperatures of internal combustion engines, etc. In any of these instances the tubular extension 5 is exteriorally threaded, as indicated at 5^a, and as such serves the function of forming a connection between the instrument and the smokestack, 25 bake oven exhaust manifold, or whatever the case may be. If the instrument is inserted in the exhaust manifold of an internal combustion motor or engine the tube 9, containing the rod 11, will extend into the manifold and the hot exhausting gases will impinge thereon. The tube 9 is constructed of a material having a comparatively high coefficient of expansion while the rod 11 is constructed of a material having an existing 30 low coefficient of expansion. Hence when the tube 9 is subjected to gases of high temperature, it tends to expand longitudinally and as the rod 11 does not tend to expand it will settle downwardly in the tube 9, the plunger 12 will move downwardly with the rod 11 and the main operating lever 14 will swing about its pivot 15 in the direction of arrow *b*. Link 25 will also move in the same direction and the segment 35 22 will swing about its pivot 23 towards the right, thus transmitting a rotary movement to the spindle 20, the pinion 21 and the indicating hand 26 in a clockwise direction. The amount of movement imparted depends entirely upon the temperature to which the tube 9 is exposed, or, in other words, to the amount of expansion which takes place in the tube.

40 If the temperature of the gases decreases the tube will contract or shorten, thus forcing

the rod 11 and the plunger 12 upwardly. This upward movement is in turn transmitted through the connection 13 to swing the lever 14 about the pivot 15 in a direction opposite to the arrow *b* and a pull is thus exerted on the link 25 which will cause the segment to swing towards the left. This in turn transmits a reverse or contra-clockwise movement to the spindle and indicating hand and a lower temperature reading will be indicated. 75

During contra-clockwise movement of the indicating hand the spring 46 is extended and during a clockwise movement of the indicating hand the spring is contracted. 80 The spring, however, always remains under tension so that a sufficient pull is exerted at all times to take up all play, back lash and lost motion. This is exceedingly important as correct temperature readings could not 85 otherwise be obtained.

It has been stated in the preamble to the specification that temperature indicating instruments constructed along the lines specified have been constructed and used, but had, 90 practically speaking, been abandoned for numerous reasons, among them being deterioration, disintegration and change in expanding and non-expanding elements by which the instruments were actuated. 95

I have discovered that if the tube 9 is constructed of Monel metal and the rod 11 of a fused slag or quartz a dependable uniform operation can be secured as Monel metal will stand high temperatures without 100 oxidizing and without affecting the coefficient of expansion of the Monel metal; this being also true as far as fused slag or quartz rods are concerned, and it is accordingly important that these two specified elements be 105 employed, to-wit, Monel metal and quartz rods, as they are the only two elements I have so far discovered which are positively dependable. The tubular extension 5 and the plunger 12 may be made of any suitable metal as they are not subjected to high temperatures. However, it is essential that they be made of the same metal so that they will both simultaneously contract and expand at a uniform ratio. 110

It is also more or less important that the same metals be employed within the casing so that a uniform expansion of contraction ratio is maintained as all the members are under certain conditions subjected to more 115 or less conducted or radiant heat.

It often happens that instruments of this character are subjected to abuse. For instance, the tube 9 may be subjected to higher temperatures than are indicated on the 120 graduated dial, and while this may not do any damage to the tube 9 and the interior rod 11, it will cause an excessive expansion or elongation of the tube and a similar excess movement of the main operating arm 125 130

14 and the segment 22. That is, the segment will swing about the pivot 23 to such an extent that the teeth on the segment will move out of mesh or engagement with teeth 5 on the pinion 21. The hair spring cooperating with the pinion will in that case unwind and the indicating hand 26 will lose its adjustment. To prevent disengagement of the pinion and the segment 22 a stop lug 10 60 is employed. This lug moves into engagement with the upper post 19 of the gauge movement and thereby limits the movement of the main operating arm 14 and the segment 22. In other words, the movement 15 the end of the segment reaches the pinion 22 lug 60 engages the post 19 and further movement or disengagement of the segment and pinion is prevented.

While certain features of the present invention have been more or less specifically described and illustrated, I wish it understood that various changes may be resorted to within the scope of the appended claims, and also that the materials and finish of 25 the several parts employed may be such as the experience and judgment of the manufacturer may dictate or varying conditions may demand.

Having thus described my invention, what 30 I claim and desire to secure by Letters Patent is:—

1. In a device of the character described, a casing having a graduated temperature indicating dial mounted thereon, a base plate 35 mounted within the casing, a top plate, a spindle journaled between the plates and having a gear pinion mounted thereon, a gear segment pivoted between the plates and intermeshing with the pinion, an adjustable lever extension on said gear segment, a main operating lever pivoted within the casing, a link pivotally secured to the adjustable extension on the gear segment, an adjustable connection between the opposite end 40 of the link and the main operating lever, means for imparting movement to the main operating lever, and a spring connected at one end with the casing and at the opposite end with the adjustable extension on the 45 gear segment.

2. In a device of the character described, a casing having a graduated temperature indicating dial mounted thereon, a base plate mounted within the casing, a top plate, a 55 spindle journaled between the plates and having a gear pinion mounted thereon, a gear segment pivoted between the plates and intermeshing with the pinion, an adjustable lever extension on said gear segment, a main operating lever pivoted within the casing, a link pivotally secured to the adjustable extension on the gear segment, an adjustable connection between the opposite end 60 of the link and the main operating lever, means for imparting movement to the main 65

operating lever, a spring connected at one end with the casing and at the opposite end with the adjustable extension on the gear segment, and means for limiting pivotal movement of the gear segment to prevent the gear segment from swinging out of mesh with the pinion.

3. In a device of the character described, a casing having a graduated temperature indicating dial mounted thereon, a base plate mounted within the casing, a top plate, a spindle journaled between the plates and having a gear pinion mounted thereon, a gear segment pivoted between the plates and intermeshing with the pinion, an adjustable lever extension on said gear segment, a main operating lever pivoted within the casing, a link pivotally secured to the adjustable extension on the gear segment, an adjustable connection between the opposite end of the link and the main operating lever, means for imparting movement to the main operating lever, a spring connected at one end with the casing and at the opposite end with the adjustable extension on the gear segment, and a stop lug mounted on the main operating lever to limit the movement of the main operating lever and the gear segment.

4. In a device of the character described, a casing having a graduated temperature indicating dial mounted thereon, a base plate mounted within the casing, a top plate, a spindle journaled between the plates and having a gear pinion mounted thereon, a gear segment pivoted between the plates and intermeshing with the pinion, an adjustable lever extension on said gear segment, a main operating lever pivoted within the casing, a link pivotally secured to the adjustable extension on the gear segment, an adjustable connection between the opposite end of the link and the main operating lever, means for imparting movement to the main operating lever, a spring connected at one end with the casing and at the opposite end with the adjustable extension on the gear segment, a pivotal connection between the base plate and the casing at a point adjacent the spindle, and an adjustable connection between the opposite end of the base plate and the casing to permit swinging movement of the base plate about the pivotal connection.

5. In a device of the character described, a casing having a graduated dial mounted thereon, a gauge movement within the casing, a pointer carried by the gauge movement and movable over the dial, a pivotal connection between one end of the gauge movement and the casing, and an adjustable connection between the opposite end of the gauge movement and the casing to permit swinging of the gauge movement about the pivotal connection.

6. In a device of the character described, a casing having a graduated dial mounted thereon, a gauge movement within the casing, a pointer carried by the gauge movement and movable over the dial, a pivotal connection between one end of the gauge movement and the casing, an adjustable connection between the opposite end of the gauge movement and the casing to permit 10 swinging of the gauge movement about the pivotal connection, said adjustable connection comprising a bolt extending through a slot in the casing, a post through which the bolt passes, a second post, a threaded rod 15 connected with the first named post and extending through the second named post, and adjusting screws mounted on the rod on opposite sides of the second named post.

7. In a device of the character described, 20 a tube constructed of expandible material, a casing to which the tube is attached, a seat in one end of the tube having a semi-spherical depression formed therein, a rod of substantially non-expanding material engaging 25 the seat and supported thereby, the end of the rod being rounded to engage the depressed seat, a plunger engaging the opposite end of the rod, a rounded depressed seat in the plunger, and a rounded end on the 30 rod to enter the seat.
